UNITED STATES PATENT OFFICE.

HARRY M. ROBERTSON, OF ROCKVILLE, MARYLAND, ASSIGNOR TO AMERICAN DRESSLER TUNNEL KILNS, INC., OF NEW YORK, N. Y., A CORPORATION OF NEW YORK.

GAS-PRODUCER-CONDUIT SYSTEM.

Application filed May 19, 1920. Serial No. 382,594.

The general object of my present invention is to provide an improved conduit system for passing the heating gas from a gas producer to a furnace or other apparatus in which the gas is used. The invention comprises improvements in the conduits proper and in the relative arrangement of the conduits, gas producer and the furnace or other apparatus in which the gas is utilized, devised with the specific objects in view of providing a compact and convenient arrangement of the producer, distributing conduits, and furnace or the like, whereby ground space is economized while at the same time a conduit system of sufficient length is provided to effectually clean the gas in its passage therethrough and which may be readily cleaned from time to time as occasion requires.

20 The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of my invention.

25 Of the drawings;

Fig. 1 is a somewhat diagrammatic plan view of a gas producer, furnace and the conduit system for passing gas from the producer to the furnace.

30 Fig. 2 is a partial sectional elevation on the line 2—2 of Fig. 1.

And Fig. 3 is a sectional elevation taken on the broken line 3—3 of Fig. 1.

In the drawing A represents a gas producer which may be of any usual or suitable type delivering hot unclean gas through its outlet pipe A'. The latter is shown as leading horizontally from the producer adjacent its upper end. The outlet pipe A is connected at its outer end to a downcomer pipe A² connected to the section B of a conduit system in which the gas is cleaned and through which it is passed to a furnace such as the kiln H, or other apparatus for using the gas. As shown this conduit system comprises sections B, B', B², B³, B⁴, and B⁵ which unite to form a continuous conduit looped about the producer. The sections B² and B⁴ are parallel to one another and extend transversely to the section B, to the op-

posite ends of which the sections B² and B⁴ are connected by the sections B' and B³, respectively, which bend around the producer A located between them. The ends of the sections B² and B⁴ remote from the producer 60 are connected to one another by the section B⁵ which is parallel to the section B. While I regard the special form of the conduit system just described, as the best form devised by me for use in a plant of the particular character disclosed in detail herein, it will be obvious to those skilled in the art that my invention in certain of its aspects is not restricted to this or any other particular conduit shape.

70 Valves or dampers C and C' are employed to close communication whenever necessary or desirable between the conduit section B and the conduit sections B' and B³ respectively. Valves or dampers C² and C³ are 75 employed to close communication when necessary or desirable between the conduit section B⁵ and the conduit sections B² and B⁴ respectively. B⁶ and B⁷ represent service outlets opening from the conduit sections 80 B² and B⁴ respectively as shown. The invention, while applicable to gas fired furnaces generally, is of especial utility in plants in which the furnace fired is a continuous tunnel kiln, and in the plant shown the 85 outlets B⁶ and B⁷ deliver gas to the combustion chambers I of a continuous tunnel kiln H of the Dressler type which runs transversely to the length of the conduit sections B² and B⁴ and is located above said sections. 90 The two combustion chambers I are supported on the usual masonry benches H' provided for the purpose in the main chamber of the kiln H at opposite sides of the usual trackway H² for the cars by which ware is moved through the furnace. One outlet passage B⁶ and one outlet passage B⁷ pass upward through the corresponding bench H' to one of the combustion chambers I, while the other outlet passages B⁶ and B⁷ pass up through 95 the second bench H' to the combustion chamber mounted thereon. Each of the outlets B⁶ and B⁷ is provided with a cut off valve or damper K, shown as mounted in a horizontal slideway in the corresponding bench H'. Air for the combustion of the gas is supplied to the combustion chambers I in any usual or suitable manner. As shown 100 this air is supplied to the ends of the combustion chambers adjacent the gas outlets 105 110

B⁶ from the conduit sections B² and B⁴ through headers L and pipes L' forming part of the goods cooling system in the cooling zone of the kiln.

- 5 The conduit formed by the sections B, B', B², B³, B⁴ and B⁵ will ordinarily and preferably be formed of masonry which comprises a fire brick lining and which is imbedded in the ground. Baffles E in the form of brick arches depend from the roofs of the conduit sections B, B' and B³, approximately half-way to the conduit floor. Each of these baffles extends transversely of the portion of the conduit in which it is located. Baffles F alternate with the baffles E in the conduit sections B' and B³. The baffles F, each of which extends transversely of the portion of the conduit in which it is placed, are in the form of brick walls extending upward from the floor of the conduit approximately halfway to the top of the latter. Clean out openings B⁹ are provided along the conduit sections B, B' and B³ at convenient points for removal of soot, ashes or the like deposited from the gas in the conduit between the various floor arches F. Advantageously these openings B⁹ open into the pit in which the producer is located. The floor A¹⁰ of this pit may advantageously be at, or below, the level of the upper side of the bottom wall of the conduit. These openings B⁹ are normally closed by doors G which may be cast iron doors of the type usually employed for such purposes. A clean out stack D opens at its lower end into the conduit section B⁵, and, as shown, inspection pits B⁸ are located at the outer ends of the portions B² and B⁴ in line with the section B⁵.
- In the normal contemplated mode of operation of the apparatus shown, the dampers C and C' are open, and the dampers C² and C³ are closed. The hot gas passing into the conduit system through the downcomer A² from the producer A divides in the section B, part passing through the sections B' and B² to the outlets B⁶ and through the latter into the combustion chamber I of the kiln H, while the remainder of the gas passes through the conduit sections B³ and B⁴ to the outlets B⁷ and through the latter into the combustion chambers L. As the gas passes from the downcomer A² to the outlets B⁶ and B⁷ soot, ashes and tar are thrown out of the gas, as the gas streams bend up and down in passing the baffles E and F and collect on the walls, and particularly on the bottom wall of the conduit. If the conduit is suitably proportioned, the gas leaving the conduit through the outlets B⁶ and B⁷ will be sufficiently cleaned. With the arrangement shown in which the conduit is connected to the side of the producer A remote from the furnace H, it is possible to obtain sufficient length of conduit in each branch of the double connection from the

producer to the furnace for efficient cleaning with the producer located in close proximity to the furnace thus economizing in the use of ground space required for the plant as a whole.

When it is desirable to clean out the conduit one branch is cleaned at a time. To clean the branch comprising the sections B' and B² the valve C is closed, after which the corresponding clean out doors G are opened, and the material deposited on the floor of the conduit is removed through the doorways B⁹. When it is desired to more thoroughly clean this conduit branch, as may be necessary from time to time, the damper C² is opened and a fire is started in the conduit to burn out the soot and tars deposited on the walls of the conduit, the stack D providing the necessary draft. In cleaning the conduit branch comprising the sections B³ and B⁴, the dampers C' and C³ will be open, and the dampers C' and C² will be closed. It will be understood, of course, that cleaning either branch of the gas delivery conduit, the dampers K controlling the corresponding delivery outlet B⁶ or B⁷ will be closed. By cleaning the conduit, one branch at a time as described, the supply of gas to the furnace need never be totally interrupted, though ordinarily in a furnace of the type illustrated something less than the full amount of gas normally supplied to the furnace will be given the latter when a cleaning operation is being carried out. If, as shown, the delivery conduit passes under furnace and all portions of its bottom wall are at the same level, it is necessary to make the bottom level of the producer pit somewhat lower than would ordinarily be required otherwise, but this has a compensating advantage, in that if the producer is fed at the top, as is usual, it is not necessary to elevate the coal fed into the producer as high as would otherwise be required. The formation of the delivery conduit with two delivery branches B', B², and B³ and B⁴ separately connected to the combustion chambers of a tunnel kiln crossing the two branches is especially advantageous where, as is frequently the case it is desirable to introduce combustible gas into each of the elongated combustion chambers at spaced apart points along the length of the latter.

While, in accordance with the provisions of the statutes I have illustrated and described the best form of my invention now known to me it will be apparent to those skilled in the art that changes may be made in the form of the apparatus disclosed without departing from the spirit of my invention, as set forth in the appended claims and that certain features of the invention may sometimes be used to advantage without a corresponding use of other.

Having now described my invention, what

I claim as new and desire to secure by Letters Patent, is:

1. The combination with a gas producer of a delivery conduit comprising a central portion located at one side of the producer and connected to the gas outlet of the producer and end portions extending transversely away from said central portion at opposite sides of the producer, and projecting beyond the side of the producer remote from that at which the central portion of the conduit is located, said end portions being provided with means for cleaning the gas, and clean out openings at spaced points along said end portions.

2. The combination with a gas producer of a delivery conduit comprising a central portion located at one side of the producer and connected to the gas outlet of the producer and end portions extending transversely away from said central portion at opposite sides of the producer and projecting beyond the side of the producer remote from that at which the central portion of the conduit is located, each of said end portions being formed with clean out openings, and dampers for disconnecting said central portion from either end portion.

3. The combination with a furnace, of a gas producer at one side of the furnace, and a gas delivery conduit looped about the producer and connected to the latter at the side of the producer remote from the furnace, and provided with delivery outlets from each branch of the loop to the furnace.

4. The combination with a gas producer, of a stack, a delivery conduit looped about the producer and having its central portion connected to the producer at one side of the latter, and its end portions connected to said

stack at the opposite side of the producer valves adjacent the stack and the connection to the producer for disconnecting either end portion of the conduit from the producer and from the stack at will, each portion of the conduit being formed with at least one clean out opening and at least one valved delivery outlet between the stack and the producer connection.

5. The combination with a furnace, of a gas producer at one side of the furnace and a gas conduit looped about the producer with its end portions passing under the furnace and provided with delivery outlets to the furnace, said conduits being connected to the producer at the side of the latter remote from the furnace and having its end portions spaced apart so that said delivery outlets from the two end portions open to the furnace at points displaced longitudinally of the furnace.

6. The combination with a furnace, of a gas producer at one side of the furnace, a plurality of ducts leading from the producer to the furnace and normally supplying gas to the latter, a stack located at the opposite side of the furnace from the producer and connected to said ducts, and dampers controlling communication between the ducts and the producer, furnace and stack, whereby each duct may be connected to the producer and furnace and disconnected from the stack in normal operation, and may be connected to the stack and disconnected from the producer and furnace for cleaning.

Signed at city of New Castle in the county of Lawrence and State of Pennsylvania this 14th day of May, A. D. 1920.

HARRY M. ROBERTSON.
